RAIL JOINT TREAD BRIDGE

William G. Buhler, Jerseyville, Ill.

Application January 5, 1946, Serial No. 639,214

4 Claims. (Cl. 238—218)

1

This invention relates to rail joint tread bridges and consists of the novel construction hereinafter disclosed.

As is well known in the art, one of the principal difficulties in track maintenance is the prevention of so-called low joints between rail ends of the track.

The requirement of spacing adjacent ends of the rails to provide expansion space necessarily results in the downward deflection of rail ends at the joint, gradually weakening the rails at the adjacent ends and causing, in many cases, broken joints, as will be readily understood.

Furthermore, the constant downward deflection of the rails at the adjacent ends causes tamping down of the roadbed beneath the supporting ties at the joints, causing pockets in which water accumulates, and the constant downward deflection of the rail forces out the roadbed support, mainly at the joints.

It is a matter of common knowledge that this constant disintegration of the roadbed at the rail joints is a major item connected with track maintenance.

One of the primary objects of the present invention is to provide a rail joint that tends to obviate or overcome these defects with the present rail joint. First, by providing the matching edges of the rail with complementary angular cuts so that the weight of the railroad equipment at the joints is distributed and, second, to provide for bridging the joints in such a manner that part of the weight of the railroad equipment is carried by the fish plate across the joint at the adjacent ends of the rails.

Another object of the invention is to provide a construction which may be readily incorporated with standard rail track equipment, and which may be adjusted to accommodate the carrying tread of the rail joint to the standard tread of the railroad car wheels, with provision for the necessary adjustment for the proper tread of the wheels of the railroad equipment, particularly on curved sections of the track.

These, as well as additional advantages, will be apparent from the following detailed description of the invention taken in connection with the accompanying drawing, in which:

Fig. 1 is a top plan view of a joint constructed in accordance with the present invention, with certain of the structure being indicated in dotted lines;

Fig. 2 is a side elevation of the rail joint, incorporating the present invention, with part of the structure being indicated in dotted lines;

2

Fig. 3 is an enlarged cross section through the joint taken substantially on the line 3—3 of Fig. 1; and

Fig. 4 is a perspective view illustrating the form of a wedge block employed in the construction as a means of adjusting the elevation of the fish plate.

In the embodiment of the invention selected for illustration, the adjacent ends of rails 1 are cut at complementary angles, as indicated at 2. Otherwise, the rails are of a standard construction including a base section 3, a tread section 4 connected by a web 5 through which there are openings 6.

15 The crown of the tread section 4 is rounded at its lateral edges and is adapted to conform to the tread face of a wheel 7 of standard construction, which wheel includes the inner side flange 8. The standard crown surface of the rail 20 has a curved contour 9, formed on a predetermined radius. The tread surface, as is usual in railway car wheels, if formed on a predetermined curvature 10, which tapers to the outer face of the wheel, as clearly illustrated in Fig. 3.

25 This construction of a car wheel will be recognized as standard, and is required because of the necessary formation of the wheel to provide for the proper tracking of the wheel to the rail, both on straight and curved sections of the railway track.

30 It will be understood that on curved sections of track, the outer wheels ride on the radius 9 of the flange section of the wheel against the inner edge of the rail, and the outer portion of 35 the tread of the wheel, because of its tapered periphery in this area, extends above the plane of the crown of the rail 4.

38 What has been described relates to standard rail and car wheel construction, but has been 40 described in order that the application of the particular construction embodying the present invention may be better understood.

The structure of the present invention includes an inner plate 11 formed with a top flange 12 and a bottom flange 13, the upper face of the flange 12 fitting against the under-inclined surface of the standard tread section of the rail 4, and the underface of the flange 13 being tapered to conform to the upper face of the flange section 3 of the rail, as will clearly appear from Fig. 3 of the drawing. The plate 11 is provided with bolt openings 14.

45 The outer member of the rail joint includes a plate formed with a lower section 15 in the form of an elongated plate with recesses 16 in its front

face, which plate has a plane horizontal bottom face 17 and an inclined upper face 18. The upper face 18 inclines inwardly and is complementary formed with the lower wall of the outer area of the rail tread 4.

This lower section 15 is provided with a series of bolt openings 19 therethrough. Integrally formed with the section 15 of the outer member of the joint is a section 20, having recesses 21 in the front face thereof. The upper edge of the section 20 is formed on a convex curve, as illustrated at 22 (Fig. 2), and inclines inwardly, as illustrated at 23 in Fig. 3.

By reference to Fig. 3, it will be noted that the top face of the member 19 is elevated above the crown of the rail at its high point, and that because of the curvature 22, it is substantially in the same plane as the crown of the rail at each end thereof. Therefore, as the car wheel passes over the joint, it is supported near its outer face entirely by the upper surface of the outer member of the joint, which carries a major portion of the load, the remainder of which, particularly on curved sections of the track, rides on the radius 9 of the inner flange of the wheel against the inner curved portion of the tread-section of the railway rail.

The angle cut at the ends of the rails is arranged so that the outer edge of the expansion is approximately at the medium line of the outer plate. Therefore, the load will be carried across the expansion space by the upper face of the outer plate at its highest elevation.

In order to provide a practical means of properly adjusting the relative elevation of the top face of the outer rail joint member and the upper face of the rail, I have provided a convenient means of constructing the joint, so that the upper tread surface thereof will be accurately elevated in respect of the tread section of the rail in order to carry the load over the expansion space between the rails by contacting the outer edge of the periphery of the car wheel. This is accomplished by providing wedge blocks 24, which have a plane horizontal upper face 25 and an inclined lower face 26. A plurality of these wedge blocks 23 may be inserted beneath the face 17 of the outer joint member. These blocks are adjusted along the outer plate and positioned at the proper distance inwardly of the rail. Thus, the elevation of the top face or tread of the outer joint member may be adjusted to permit the proper tread of the car wheel regardless of the difference in radii of the curved track construction.

After the wedge blocks 24 have been positioned to get the required elevation of the outer joint member, they may be welded in place so as to give a permanent support to the outer joint member and, since the upper face of the wedge block is horizontal, it matches the underside 17 of the outer joint member.

Thus, the strain will be relieved on the joining members or bolts which clamp the outer and inner plates of the joint together. It will be understood that the two plates of the joint are clamped together by a plurality of bolts 27 mounted in the openings 6, 14 and 19.

In order to obtain a wedging action and a rigid support for the outer plate member and, because of the fact that it is necessary to change the relative position of the inclined face 18 in respect to the underinclined face of the rail tread section for different adjustments of the outer joint member, it is preferred that where the

spacing occurs, that shims 28 be inserted between the face 18 and the underface of the outer portion of the tread section of the rail, as illustrated in Fig. 3.

It should also be noted that, in order to accommodate the raising and lowering of the outer member of the joint, the opening 19 should be formed slightly oval-shaped, with the greatest dimension vertical.

From the foregoing description, it will be understood that I have provided a highly satisfactory rail joint that effectively relieves excessive downward movement on the adjacent ends of the rails by bridging the joint so that a substantial part of the load is carried on the outer member of the joint.

It will also be understood that I have provided for adjustability of the joint to accommodate it to the requirements of track construction in such a way as not to interfere with the proper tracking of the wheel, particularly on curved sections of the track.

It will also appear that the construction provides for an extremely rigid and durable support for joints of railway rails.

It will be evident, therefore, that the invention fully accomplishes the purposes and obtains the advantages heretofore set out.

It should also be understood that I do not confine myself to the exact structural formations, as illustrated, but that the invention may be varied in certain particulars without departing from the scope of the invention.

What I claim is:

1. For combination with adjacent ends of standard railway rails, a rail joint comprising an outer plate extending parallel with the outer rail surfaces and across the adjacent side face of the rails and having a base section dimensioned and formed to be fastened between the underface of the rail tread sections and spaced from the upper faces of the rail flange and an integral upper section having a top surface inclined upwardly from each end forming a central section that extends above the crown of the rail ends at the joint, wedge blocks inserted within the space between the bottom surface of said plate and the upper face of the rail flange whereby the elevation of said plate may be adjusted relative to the crown of the rail ends, an inner plate positioned between the undersurface of the rail tread sections and the upper face of the rail flanges, and means for clamping said plates and said rail ends together.

2. A rail joint for splicing adjacent rail ends cut on complementary angles comprising an outer plate extending parallel with the outer rail surfaces having a base section dimensioned and formed to be fastened between the underface of the rail tread sections and spaced from the upper face of the rail flange and an integral upper section having a top surface inclined upwardly from each end forming a central section that extends above the crown of the rail ends and across the area of the angle matching faces of the rail ends, wedge blocks inserted within the space between the bottom surface of said plate and the upper face of the rail flange whereby the elevation of said plate may be adjusted relative to the crown of the rail ends, an inner plate positioned between the underface of the rail tread sections and the upper face of the rail flanges, and means for clamping said plates and said rail ends together.

3. For combination with adjacent ends of

5

standard railway rails, a rail joint comprising an outer plate extending parallel with the outer rail surfaces and across the adjacent side face of the rails and having a base section dimensioned and formed to be mounted between the underface of the rail tread sections and spaced from the upper face of the rail flange and an integral upper section having a top surface inclined upwardly from each end forming a central section that extends above the crown of the rail ends at the joint, wedge blocks mounted in spaced relationship between the bottom surface of said plate and the upper face of the rail flange whereby the elevation of said plate may be adjusted relative to the crown of the rail ends, an inner plate extending parallel with the inner rail surfaces and positioned between the underface of the rail tread sections and the upper face of the rail flanges, and means for clamping said plates and said rail ends together.

4. For combination with adjacent ends of standard railway rails, a rail joint comprising

6

an outer plate extending parallel with the outer rail surfaces of the rails having a base section dimensioned and formed to be mounted between the underface of the rail tread sections and spaced from the upper face of the rail flange and an upper section having a top surface inclined upwardly from each end forming a central section that extends above the crown of the rail ends at the joint, a plurality of wedge blocks mounted in longitudinally spaced relationship within the space between the bottom surface of said plate and the upper face of the rail flange whereby the elevation of said plate may be adjusted relative to the crown of the rail ends, means rigidly attaching said blocks to the rail flanges, an inner plate positioned between the underface of the rail tread sections and the upper face of the rail flanges, and clamping means for connecting said plates and said rail ends together and for permitting relative vertical adjustment of said outer plate.

WILLIAM G. BUHRER.
